UNITED STATES PATENT OFFICE.

JOHN A. CRAWFORD, OF PHILADELPHIA, PENNSYLVANIA.

WASHING-MACHINE AND PUMP MECHANISM THEREFOR.

1,382,479.

Specification of Letters Patent. Patented June 21, 1921.

Application filed September 3, 1919. Serial No. 321,375.

To all whom it may concern:

Be it known that I, JOHN A. CRAWFORD, a citizen of the United States, residing at Philadelphia, in the county of Philadelphia and State of Pennsylvania, have invented new and useful Improvements in Washing-Machines and Pump Mechanism Therefor, of which the following is a specification.

The invention relates to washing, and more particularly to washing machines for use in washing clothes and the like and has for an object to provide a washing machine and pumping mechanism therefor for use in pumping the water or other fluid generally employed in connection with the washing of clothes in a machine of this character.

Among other features the invention comprehends a container carried on a suitable base with a pump disposed upon the base and connected by suitable piping with the container or clothes receiving vessel, the pump being also so disposed to be operatively connected with the usual motor adapted to the driving of the mechanism of the washing machine so that when the washing operation has been completed the pipe from the pump to the clothes receiving vessel can be opened and the pump placed in operation to pump out the soiled water and dirt to convey the same to some convenient place of disposal.

My invention is particularly adapted for the domestic washing machines ordinarily found in the household and which usually are operated by an electric motor forming a part of the equipment of the machine. These machines ordinarily have a drain pipe for draining the used water and dirt from the interior of the vessel for holding the clothes but in draining out the water the same must be received in a bucket or other suitable receptacle and then manually carried to the house drain or stationary tub. I aim to provide a construction whereby this manual labor is done away with and in so doing I provide a pipe which I will term a drain pipe and which connects with a suitable pump or any convenient form of turbine which has another pipe extending along the washing machine to a convenient point where the out-flow therefrom will drain into a stationary tub or the like. The pump I have arranged convenient to the motor and I provide suitable means whereby the pump can be geared up with the motor and operated to forcibly remove the water from the

interior of the vessel of the washing machine and pump it to the place of disposal, the operation of opening the drain valve in the drain pipe and throwing in the clutch for connecting the pump in operative relation with the motor, being accomplished by a mechanism which by a single movement thereof performs both operations.

In the further disclosure of the invention, reference is to be had to the accompanying drawings constituting a part of this specification, in which similar characters of reference denote corresponding parts in all the views, and in which,

Figure 1—is a fragmentary perspective view of a washing machine showing my apparatus.

Fig. 2—is a fragmentary side elevation of the washing machine in slightly enlarged form, showing the pump, motor and component parts in elevation.

Fig. 3—is a fragmentary vertical sectional view through the clutch mechanism between the pump and motor, and

Fig. 4—is a fragmentary vertical transverse sectional view through the clutch showing the operating member.

Referring more particularly to the views the washing machine in its entirety is indicated by the numeral 10 and comprehends among other things, a base 11 having suitable uprights 12, which support a container or vessel 13 for the clothes, a suitable drip board 14 being also provided. A motor 15 is mounted on the base and through suitable driving mechanism 16, is connected with the interior operating agitators (not shown) of the washing machine, inclosed in a casing 17 and a form of wringer 18 which may also be operated through the medium of the motor 15.

Mounted on the base 10 is a pump 19 and a drain pipe 20 from the vessel or container 13, which connects with the pump 19, a suitable valve 21 being disposed in the drain pipe for opening or closing the latter when the valve is opened or closed. A second pipe 22 extends from the pump 19 to a point adjacent one end of the washing machine where the pipe 22 extends upwardly to have its outlet end 23 project through an opening or slot 24 in the drip board 14 so that the water flowing out through the outlet 23, can readily pass on into a stationary tub 25.

The connection between the motor 15 and pump 19 comprises a clutch element 26 keyed

to the shaft 27 of the motor with a second clutch element 28 mounted to slide longitudinally on the shaft 29 of the pump, said clutch element 28 however being keyed relative to the shaft by a key 30 whereby although such clutch element 28 can slide longitudinally on the shaft, it will rotate therewith. Spanning a reduced portion of the clutch element is a yoke 31 of a clutch lever 32 pivoted on a bracket 33 extended from the pump with the upper end of said clutch lever having pivotal connection with an arm or connecting link 34 which has pivotal connection with the free offset end 35 of a valve handle 36 in the nature of an operating lever and which latter receives the projecting stem 27 of the valve 21.

Now assuming that the washing machine is in use to wash clothes, it will be seen in Fig. 2, that the clutch elements 26, 28, will be relatively disconnected, the turbine or pump being now in non-operative position with the valve 21 closed, although the motor 15 will of course be operating to perform its function of driving the agitators of the washing machine. Now when the clothes have been thoroughly washed and it is desired to drain the soiled water and accumulated dirt from the interior of the vessel, the lever 36, shown in Fig. 2 in its closed position, is swung downwardly into its open position as shown in Fig. 1; thus opening the valve 21 and simultaneously moving the clutch element 28 into engagement with the clutch element 26. This operation of the operating lever, simultaneously opens the drain pipe 20 and places the pump in operation so that the latter will pump the water and accumulated dirt from the interior of the vessel of the washing machine through the pipe 20 into and through the pump and thence through the pipe 22 to the drip board 14 from which the water passes into the stationary tub 25. By swinging the lever from the position shown in Fig. 2, to the position

shown in Fig. 1, relative disengagement of the clutch elements is accomplished and simultaneously the valve will be moved to closed position, this operation being accomplished without necessitating the stopping of the motor or interfering with the operation of the motor in any manner.

Although I have shown a particular form of construction of my device, it will be understood that various slight changes can be made to accommodate the mechanism to different forms of washing machines; that I aim to provide a device particularly adaptable for household washing machines in which simplicity of operation and ease in manipulation is a requirement and that various slight changes may be made from what is shown in the drawings and described in this specification, without departing from the spirit of the invention, the scope of which is defined in the appended claim.

Having described my invention, I claim—

A washing machine comprising a frame, a receptacle supported in the upper part of the frame, a motor supported by the lower part of the frame, a pump on the frame adjacent the motor, an outlet pipe leading from the bottom of the receptacle to the pump, a valve in the pipe, a handle for actuating the valve, said handle having an extension thereon extending beyond its connection with the valve, an outlet pipe for the pump, a clutch for connecting the pump with the motor, a bracket on the pump, a clutch lever pivoted to the bracket and engaging with the clutch and a link having one end connected to the clutch lever and its other end connected with the extension on the handle for releasing the clutch when the handle is moved to close the valve and for engaging the clutch when the handle is moved to open the valve.

In testimony whereof I affix my signature,

JOHN A. CRAWFORD.
